ANTISKID DEVICE

Filed Feb. 9, 1929.

Inventor:
Arthur G. FitzGerald
by Harry Smith, Harry
Hays.

UNITED STATES PATENT OFFICE

ARTHUR G. FITZ GERALD, OF WEST NEWTON, MASSACHUSETTS

ANTISKID DEVICE

Application filed February 9, 1929. Serial No. 338,760.

This invention relates to anti-skid devices for vehicles and aims to provide a novel and improved device having, among others, the advantages hereinafter described.

5 In the drawing of one embodiment of my invention illustrated and described herein,

Fig. 1 is a plan showing the device with one end secured to the usual circumferential or side chain partly broken away;

10 Fig. 2, a detail of the lower face of one end of the device illustrating the manner of locking the ribbed band to the strap member;

15 Fig. 3, a development of the band member to show substantially its original form;

Fig. 4, a detail plan of a modified form of construction of locking means for the band;

20 Fig. 5, a vertical cross-section on the line 5—5, of Fig. 4; and

Fig. 6 a detail, partly sectional view of a further modified form of rib member.

This invention has particular reference to non-metallic anti-skid members, where a 25 cross-member as a strap of rubber or other suitable ice gripping material is used, and in Fig. 1 such a member 1 is shown of a maximum width about midlength and tapering toward each end, the ends being secured to 30 the usual side chains.

This member 1 is provided with anti-skid ribs 2 on its outer or tread face and they may be arranged in any desired and effective manner.

35 It is well known that such non-metallic anti-skid devices have certain advantages over the metallic ones, such as chains or bars which are in common use, as the former are more quiet and less likely to slip on dry ice and snow, and wear longer. But on wet ice or wet roads, these non-metallic members are as likely to slip as the metallic ones.

Hence, I have conceived the novel construction in which the metal and non-metallic 45 members are combined in an effective manner.

On the strap or cross member 1, Fig. 1, I secure, near each end, a band 3, of metallic or hard but ductile material of any kind 50 which is of sufficient length to permit its

ends to be bent about and beneath the ends of the strap 1 and secured thereto.

In the present case the ends of the band, Figs. 1, 2, 3, are provided with teeth 4, which, after being brought beneath the strap 1 are 55 bent and driven inwardly into the strap and thus securely lock the band 3 thereto.

The outer or tread face of the band is provided with one or more, herein two, ribs 5 running lengthwise of the band. The 60 strap is of such a length and the band is so positioned thereon that normally the band will be just above the portion of the tire tread that is in contact with the road, and the band will not, therefore, touch the road. 65

When, however, the car skids, the straps 1 in contact with the road will be slid in the opposite direction on the tire from that in which the tire is skidding and that will pull 70 downwardly the band on the end of the strap on the side toward which the car is skidding until the band contacts with the road surface, when the ribs 5 which will be positioned across the skidding path will effectively aid in preventing further skidding 75 of the car in that direction.

If preferred, of course the bands 3 can be riveted or otherwise secured to the strap 1, see Figs. 4, 5, as by screws 6, but in either case they may readily be renewed if necessary when worn out. 80

The ribs 5 may be formed as desired, for instance in Fig. 1, they are shown as struck up from a flat blank 7, Fig. 3, the edges 8, 9, of the blank, Figs. 2, 3, being also turned inward to reinforce the ribs and form bases therefor. The extensions 10, 10, 11, 11, are struck up to form ends 13 of the ribs 5, the latter being struck up between the extensions 10, 10 and 11, 11 respectively. 85 90

In Fig. 6 the ribs are formed by casting the band and ribs or by otherwise fashioning them.

The complete strap with the bands 3 on 95 either end provide the most complete and effective anti-skid device I know of and one that will outlast the conventional cross chain construction.

My invention is not limited to the particu- 100

lar embodiment thereof described and illustrated.

I claim:

1. An anti-skid device blank comprising a rectangular member having rectangular wings extending from the opposite sides near one end, the similar wings extended from the same sides near the other end and between said wings laterally extended tongues forked at their ends to provide teeth.
- 10 2. An anti-skid device comprising a key-stone shaped plate with gripping prongs on each end constructed and arranged to be driven into a strap, a triangular shaped rib on each side of the plate, said plate adapted for attachment to a cross strap for wheel side chains.

In testimony whereof, I have signed my name to this specification.

ARTHUR G. FITZ GERALD.
